NATHAN E. LEWIS, OF PLAINFIELD, NEW JERSEY, ASSIGNOR TO THE BABCOCK & WILCOX COMPANY, OF BAYONNE, NEW JERSEY, A CORPORATION OF NEW JERSEY.

BAFFLE FOR STEAM-BOILERS.

1,299,486.

Specification of Letters Patent.

Patented Apr. 8, 1919.

Application filed November 17, 1917. Serial No. 202,494.

To all whom it may concern:

Be it known that I, NATHAN E. LEWIS, a citizen of the United States, residing at Plainfield, county of Union, and State of New Jersey, have invented certain new and useful Improvements in Baffles for Steam-Boilers, of which the following is a specification.

My invention relates to a special baffle arrangement as applied to a Babcock & Wilcox boiler, and will be understood by reference to the accompanying drawings in which Figure 1 is a vertical section on the plane of the line 1—1 of Fig. 3; Fig. 2 a horizontal section on the plane of the lines 2—2 of Figs. 1 and 3; and Fig. 3 a vertical transvers section on the plane of the line 3—3 of Fig. 1. In order to make Fig. 3 appear in such position that a row of tubes in Fig. 1 will be in 10 the same line, in the drawing, as in Fig. 3, the latter has been rotated from its normal vertical position.

Referring to the drawings the numeral 1 designates a portion of the water tubes of an 25 inclined bank of tubes of a Babcock & Wilcox boiler, said tubes being connected to upper and lower headers, not shown. 2 designates the bridge wall at the rear of the furnace. Upon the bridge wall rests a line of 30 special tiles 3 which partially surround the lowermost row of water tubes. Extending forward from the bridge wall to the lower end of a transverse baffle, is a special baffle 35 made up of lower and upper tile pieces 5 and 6, respectively. The purpose of this longitudinal baffle is to deflect the gases from that part of the furnace over which it extends, and to cause them to flow upward at the left of the transverse or vertical baffle. As 40 heretofore constructed the longitudinal baffle consisted of a single line of tiles which deteriorated rapidly and permitted leakage of gases through the joints. Furthermore, explosions in the furnace loosened the tiles 45 resulting in an increase in the gas leakage.

To overcome the defects in the usual form of baffle I have designed the present form consisting of the two lines of special tiles 5 and 6. The tiles 5 rest directly upon one of 50 the rows of water tubes, the lowermost row in the arrangement shown, and the tiles 6 are so laid as to break joint with the lower tiles in both directions. As shown in Fig. 1, the joints 7 which run in the direction of

the bridge wall, are broken, that is, there is 55 an overlying tile at each such joint; and as shown in Fig. 3 the joints 8 parallel with the tubes are also covered. Leakage of the hot furnace gases between the joints is thus practically prevented. The tiles 5 and 6 are 60 symmetrical and are of the same size for all parts of the baffle except at the edges where tiles of a special size are used. These special size tile can be made by cutting them from the full size tile, or they may be specially 65 molded.

It will also be seen that the tiles 5 and 6 are so formed as to fit the water tubes, and that they are laid in such manner as to be held firmly in position so that any explosion 70 of the gases within the furnace will not displace them.

Although I have shown the baffle 5—6 placed between the two lowermost rows of water tubes, it may be placed between the 75 second and third rows from the bottom, the construction being adapted generally for use in any part of the boiler.

By closing the spaces between the tubes and the tiles 3 with a plastic material, a gas-tight joint will be provided between the top 80 of the bridge wall and the baffle 5—6.

The vertical baffle which extends from the baffle 5—6 is made up of two lines of cast iron flame plates 9 and 10 placed at angle 85 with each other, and a line of tiles 4 on the side of the baffle which comes in contact with the hottest gases. The plates 9 and 10 and the tiles 4 are formed to fit in between and around the boiler tubes. The flame plates 9 90 and 10 project inside of the furnace side of the wall 11, as shown in Fig. 3.

What I claim and desire to secure by Letters Patent of the United States is:—

1. A water tube boiler having rows of 95 water tubes and a baffle placed between two of said rows and extending parallel therewith, said baffle being composed of a plurality of layers of tile pieces so arranged that the tile pieces of one layer break joints 100 with those of the other layers in both directions.

2. A water tube boiler having rows of 105 water tubes and a baffle placed between two of said rows and extending parallel therewith, said baffle being composed of a plurality of layers of tile pieces so arranged that the tile pieces of one layer break joints

with those of the other layers in both directions, and a cross baffle extending from said longitudinal baffle across the water tubes.

3. A water tube boiler comprising rows of 5 water tubes, a furnace bridge wall, and a baffle between two of the rows of water tubes extending from the bridge wall, said baffle being composed of two lines of special tile pieces so placed with respect to each other

20 as to break joints.

4. A water tube boiler comprising rows of water tubes, a furnace bridge wall, and a baffle between two of the rows of water tubes extending from the bridge wall, said 15 baffle being composed of two lines of special tile pieces so placed with respect to each other as to break joints and extending from the bridge wall to the cross baffle which comes at the rear of the first pass.

20 5. A water tube boiler having two rows of water tubes staggered relatively to each other, and a baffle between said rows, said baffle being made up of a plurality of courses of tile pieces, the tiles of one of said courses 25 having joints at one set of water tubes, and the other course having joints between said rows of water tubes.

6. A water tube boiler having two rows of water tubes staggered relatively to each

other, and a baffle between said rows, said 30 baffle being made up of a plurality of courses of tile pieces, the tiles of one of said courses having joints at one set of water tubes and the other course having joints between said rows of water tubes, the outer faces of one 35 course being shaped to fit one set of tubes and the outer faces of another course being shaped to fit the other set of tubes.

7. A water tube boiler having two rows of water tubes staggered relatively to each 40 other, and a baffle between said rows, said baffle being made up of a plurality of courses of tile pieces, the tiles of one of said courses having joints at one set of water tubes and the other course having joints between said 45 rows of water tubes, the outer faces of one course being shaped to fit one set of tubes and the outer faces of another course being shaped to fit the other set of tubes, the courses breaking joint in both directions. 50

In testimony whereof I have hereunto signed my name in the presence of two subscribing witnesses.

NATHAN E. LEWIS.
